E. ISCHINGER

GUARD FOR PUNCH PRESSES

Filed June 26, 1920

UNITED STATES PATENT OFFICE.

ERIC ISCHINGER, OF ROCHESTER, NEW YORK, ASSIGNOR OF ONE-HALF TO FRANK KEIPER, OF ROCHESTER, NEW YORK.

GUARD FOR PUNCH PRESSES.

Application filed June 26, 1920. Serial No. 392,054.

To all whom it may concern:

Be it known that I, ERIC ISCHINGER, a citizen of the United States, residing at Rochester, in the county of Monroe and 5 State of New York, have invented certain new and useful Improvements in Guards for Punch Presses, of which the following is a specification.

The object of my invention is to make a 10 new and improved guard for a punch press of the so-called pendulum type and more especially to provide adjustments for the pivot for said guard so that the pivot may be adjusted to the right or left and forward 15 and back on the bridge, and thus make it easier to connect the guard with the ram of the press by which it is driven, thus making the guard more capable of fitting a greater variety of presses.

20 Another object of the invention is to improve the details of construction of the guard head.

This and other objects of my invention will be fully illustrated in the drawing, described in the specification and pointed out 25 in the claims at the end thereof.

In the accompanying drawing:

Fig. 1 is a front elevation of a punch press with the guard attached thereto.

30 Fig. 2 is a side elevation of the punch press with the guard shown partially in section, the section being taken on the line 2^x-2^x of Fig. 1.

Fig. 3 is a detail perspective view of the 35 adjustable pivot block of the guard.

Fig. 4 is a detail perspective view of the lower part of the adjustable pivot block.

Fig. 5 is a perspective view of the solid pivot block of the guard.

40 In the several figures of the drawing, like reference numerals indicate like parts.

Punch presses are constructed in many different sizes which are used according to the work that is to be done on them. The parts of 45 the punch presses are proportioned to the size of the presses and in mounting a guard on the frame of the press it has heretofore been necessary to make certain parts of the guard in different sizes corresponding with 50 the sizes of the presses to which they are to be attached. One dimension of the press that has to be particularly taken into consideration in mounting the guard on the press is the distance the ram block projects

out from the frame of the press. The ram 55 block is the part of the press from which the guard is driven and it is, therefore, necessary to bring the operating members of the guard into engagement with the operating member carried by the ram block. 60

In different sized presses the projection of the ram block varies considerably and in order to avoid having to build brackets of many different lengths to support the guard at the proper distance from the ram block 65 in each case, the pivot block from which the guard swings is made adjustable horizontally toward and away from the ram block of the press.

As shown in the drawings, the guard 70 comprises the swinging arm 1 which is mounted on the adjustable pivot block 2. This pivot block is shown made triangular in shape and is made up of the body member 3, into which the groove 4 is milled, and the 75 triangular shaped cover plate 5, which is clamped over the groove 4 by means of the cap screws 6, 6, 6.

A bridge member 7, which comprises a 80 bar of cold rolled steel, is adapted to support the pivot block 2 by passing thru the groove 4 so that the cover plate 5 can be tightly drawn against the front face of this bridge member and thus clamp the pivot block rigidly in place thereon. The bridge 85 member in turn is supported on either end thereof by the brackets 8 and 9 which project out from the frame of the press, being held suitably in place thereon by means of cap screws 10, 10. The bridge member is 90 hinged on the bracket 8 and is mounted to swing on the pin 11 carried in the outer end of the bracket 8. In the bracket 9 the bridge member engages into the groove 12, in which it is held in place by the pin 13, 95 which bridges the groove 12 in front of the end of the bridge member.

The pivot stud on which the guard arm 1 is mounted to swing is carried in the bearing member 14. This bearing member has a 100 serrated surface 15 that is adapted to engage the serrations provided on the bottom of the pivot block 2. The bearing member is also provided with a pair of slots 16, 16, thru which suitable cap screws 17, 17, are 105 adapted to pass and screw into the bottom of the pivot block 2, thus clamping the bearing member rigidly in place thereon.

The serrations on both the pivot block and the bearing member, when held in engagement with each other by the cap screws 17, provide a firm locking engagement of these parts that will serve to hold the bearing member at any point on the bearing block within the range of the adjustment provided by the length of the serrated surface of the bearing block and the slots provided therein.

The guard arm 1 is mounted on a head 18 in which is provided the cam slot 19. The roller 20 carried on the roller bracket 21 is adapted to engage the cam slot 19 so as to rock the head 18 and in doing so, swing the guard 1 from the left to the right thru an angle of about 80°. The movement of the roller 20 is the same as the movement of the ram block 22 on the press as the roller bracket 21 is clamped to the ram bracket 23 mounted on the ram block 22. Thus, the guard 1 swings to the right in front of the die 24 and back again each time the ram block 22 reciprocates.

The guard 1 has an auxiliary guard member 25 mounted thereon. This guard member is carried in the back of the guard 1 and projects rearwardly therefrom. While the guard 1 is intended to swing in front of the die, the guard member 25 is adapted to simultaneously sweep over the die 24 before the punch 26, carried by the ram block, makes engagement therewith. Thus, the front of the die, as well as the top thereof, is guarded in that the guard sweeps over these parts just prior to the engagement of the punch 26 with the die 24 and moves any part of the operator's hand away from in front and top of the die.

It will be understood that the length of the bridge will be proportioned to the width of the press and the pivot block 2 will be clamped in the middle of the bridge so as to bring it centrally of the press. It will also be understood that the bridge brackets will vary in length so as to support the bridge and the pivot block at the desired distance in front of the ram block and because of variations in the distance that the ram block projects out from the frame of the press, it is not necessary to vary the length of the bridge bracket in every case, but it will be sufficient to adjust the bearing member 14 in or out on the block 2 within the limit permitted so that the cam slot 19 in the guard arm 1 can engage the roller 20 carried by the ram block of the press. This makes it possible to do away with a large number of the special sizes of bridge brackets and reduces the sizes that are needed for the various makes of presses to a comparatively small number.

In Fig. 5 I have shown the triangular shaped pivot block with the bearing member integral therewith. This form of pivot

block is used when the bridge brackets are a correct fit and no adjustment back and forth is needed. The block is provided with the milled groove 4 to receive the bridge and is clamped to the bridge by the triangular cover plate 5, as above described.

I claim:

1. In a safety guard for punch presses, the combination of a pendulum member adapted to swing in front of said punch press, a bridge member supported on said punch press, a pivot carrying member supported on said bridge member, said pivot carrying member being adapted to be adjusted on said bridge member at right angles thereto toward or away from in front of said punch press, said pivot carrying member having said pendulum member mounted to swing thereon, an actuating member carried by said punch press and operating said pendulum guard on the operation thereof.

2. In a safety guard for punch presses, the combination of a bridge member adapted to be supported on the frame of the press, a pivot carrying member adapted to be clamped in place on said bridge member, said pivot carrying member being adapted to be adjusted along said bridge member and at right angles thereto towards and away from the front of the frame of the press, a pendulum guard mounted to swing on said pivot carrying member in front of said press.

3. In a safety guard for punch presses, the combination of a bridge member adapted to be supported on the frame of the press, a pivot carrying member adapted to be supported from said bridge member, a bearing member rigidly fastened to said pivot carrying member, said bearing member being adapted to be adjusted toward or away from said press and being adapted to be clamped to said pivot member, a pendulum guard mounted to swing on said bearing member.

4. In a safety guard for punch presses, the combination of a pendulum member mounted to swing in front of the frame of the punch press, an auxiliary guard member mounted on said pendulum member and projecting rearwardly therefrom, said auxiliary guard member being adapted to sweep over the die mounted on said punch press in unison with the movement of said pendulum member.

5. In a safety guard for punch presses, the combination of a bridge member mounted on the frame of said punch press and being adapted to swing with one end thereof toward and away from the frame of the punch press, a pivot member carried on said bridge member, said pivot member being adapted to be adjusted along said bridge and toward and away from in front of the frame of the press, a pendulum member mounted to swing on said pivot member.

6. In a safety guard for punch presses, the combination of a bridge member adapted to be supported at the front of on the frame of the punch press and hinged to swing in and out therefrom, a pivot carrying member carried on said bridge member and being adapted to be adjusted sideways and endways on said bridge member, a guard member adapted to swing on said pivot carrying member, means carried on said guard member to positively connect said guard member with the moving part of the punch press, said positive connection operating to swing said guard member on said pivot carrying member.
7. In a safety guard for punch presses, the combination of a bridge member adapted to be supported on the frame of the punch press, a pivot carrying member having a groove milled into the face thereof, said bridge member being adapted to engage into the groove in said pivot member, a cover plate adapted to be clamped over the groove in said pivot carrying member to clamp said pivot carrying member rigidly in place on said bridge member.
8. In a safety guard for punch presses, the combination of a bridge member supported in front of the ram of the press, a triangular shaped block having a groove therein adapted to engage the back of the bridge, a triangular shaped plate engaging the front of the bridge, said block and plate being fastened together and clamping the bridge between them, a boss carried on said block at the side of the bridge and extending transversely thereto.
9. In a safety guard for punch presses, the combination of a bridge member having a hole drilled into it near one end thereof, a supporting bracket, a pivot pin mounted in said bracket near the outer end thereof, said pivot pin being adapted to engage into the hole in said bridge member, a lock bracket having a groove provided in the front thereof, a pin mounted in said lock bracket and closing the open end of said groove, the free end of said bridge member being adapted to engage the groove in said lock bracket, said pin in said lock bracket being adapted to be held in front of said bridge member to lock said bridge member in place on said lock bracket.
10. In a guard for punch presses having a ram, the combination of a bridge member, a guard mounted to swing on said bridge member, an actuating member adjustably mounted on said ram of said punch press to operate said guard and means to adjust said guard bodily toward or away from said actuating member and means to adjust said guard along said bridge member, said bridge member being held stationary during the adjustment of said guard thereon.
11. In a guard for punch presses having a ram, the combination of an actuating member carried on said ram of said punch press said actuating member comprising a stationary bracket and an adjustable bracket mounted on said stationary bracket, a guard mounted in front of said punch press and operated by said actuating member and means to adjustably move said guard and its bearing toward and away from said actuating member.
12. In a guard for punch presses having a ram, the combination of an actuating arm carried on said ram, a bridge member, a guard mounted to swing from said bridge member, said guard having a sliding connection with said actuating member to operate said guard on the reciprocation of said ram, and means to adjustably move said guard and its bearing toward or away from said actuating member to keep it in sliding contact therewith.
13. In a guard for punch presses having a reciprocating ram, a bridge member mounted in front of said ram, an actuating member comprising a fixed member and an adjustable member mounted on said ram, a guard mounted on said bridge member, a cam member carried on said guard, said actuating member being adapted to engage with said cam member and means to adjust said guard toward or away from said ram to engage said actuating member into said cam member.

In testimony whereof I affix my signature.

ERIC ISCHINGER.
